[57] CLAIM

The ornamental design for a printers' table for use in
reproducing human eye color perceptions, as shown
and described.

DESCRIPTION

FIG. 1 is a front elevational view of a printers' table for
use in reproducing human eye color perceptions showing
my new design;

FIG. 2 is a rear elevational view thereof;

FIG. 3 is a top plan view thereof;

FIG. 4 is a left side elevational view thereof;

FIG. 5 is a right side elevational view thereof; and

FIG. 6 is a top perspective view thereof.

FIG. 1***FIG. 2******FIG. 3******FIG. 4******FIG. 5***FIG. 6
